UNITED STATES PATENT OFFICE.

JOSEPH WILLON, OF NEW YORK, N. Y.

DESIGN FOR A FRAME FOR CLOTHES-LINE HOLDERS.

SPECIFICATION forming part of Design No. 25,647, dated June 16, 1896.

Application filed February 5, 1896. Serial No. 578,167. Term of patent 7 years.

To all whom it may concern:

Be it known that I, JOSEPH WILLON, a citizen of the United States, and a resident of New York, in the county and State of New York, have invented and produced a new and original Design for a Frame for Clothes-Line Holders, of which the following is a specification.

In the accompanying drawings, forming a part hereof, Figure 1 is a perspective view of a clothes-line holder, showing my design; and Fig. 2 is a side elevation of the same, these two figures being deemed necessary to fully illustrate my design.

10 A is the frame. This is finished with a curved top *a*, the same being united with the similarly-incurved sides *b b*, and, at the part opposite end *a*, terminating in the upwardly-

15

curved portion *c*, of which the lowermost line is straight.

The design is neat and attractive, and, throughout, presents to the eye an agreeable union of symmetrical curves and outlines.

Having now fully described my invention, what I claim as new herein, and desire to secure by Letters Patent, is—

The design for a frame for a clothes-line holder, substantially as shown and described.

Signed at New York, in the county and State of New York, this 3d day of February, A. D. 30 1896.

JOSEPH WILLON.
